UNITED STATES PATENT OFFICE

160,391

AIR CIRCULATOR

Ray Rice Hutcheson, New York, N. Y., assignor to
Mimar Products, Inc., Brooklyn, N. Y., a cor-
poration of New York

Application September 7, 1949, Serial No. 4,890

Term of patent 14 years

(Cl. D26—7)

To all whom it may concern:

Be it known that I, Ray Rice Hutcheson, a citizen of the United States of America, and resident of the county of Kings, city and State of New York, have invented a new, original, and ornamental Design for an Air Circulator, of which the following is a specification, reference being had to the accompanying drawing forming a part thereof, in which

Fig. 1 is a top plan view of an air circulator embodying my new design;

Fig. 2 is a front view thereof; and

Fig. 3 is a bottom view thereof.

I claim:

The ornamental design for an air circulator, as shown.

RAY RICE HUTCHESON.
